UNITED STATES PATENT OFFICE.

JOHN A. PETERSON, OF BEVERLY, MASSACHUSETTS.

PIPE-WRENCH.

1,187,170.

Specification of Letters Patent. Patented June 13, 1916.

Application filed June 15, 1914. Serial No. 845,176.

To all whom it may concern:

Be it known that I, JOHN A. PETERSON, a citizen of the United States, residing at Beverly, in the county of Essex and State 5 of Massachusetts, have invented certain new and useful Improvements in Pipe-Wrenches, of which the following is a specification.

This invention relates to improvements in pipe wrenches and its object is to produce a wrench that is simple in construction and 10 operation and that is adapted to obtain a positive purchase upon pipes of a variety of sizes. Means to prevent lateral play of the swinging jaw of the wrench are also 15 provided.

With the foregoing and other objects in view the invention consists in the combination and arrangement of parts to be herein-after fully described in the following specification, pointed out in the claim and illustrated in the accompanying drawing which forms a part of said specification and in which—

Figure 1 is a side elevation of my improved wrench applied to a pipe of medium size. Fig. 2 is a similar view of the device applied to a very small pipe. Fig. 3 is a view of the wrench with the parts in altered position applied to a large pipe. Fig. 4 is 25 a plan of the wrench. Fig. 5 is an inverted plan. Fig. 6 is a plan of a portion of the wrench and is taken on line 6—6 of Fig. 3. Fig. 7 is a section taken on the line 7—7 of Fig. 6.

Like reference characters indicate corresponding parts throughout the several views.

1 designates the bifurcated fixed jaw of my wrench which is channeled as at 2, which 40 portion is extended to the surface at 3, and provided with an integral handle 4. Within the channeled portion of the fixed jaw an angular terminally bifurcated swinging jaw 5 is adjustably disposed upon a bolt 6 which 45 is adapted for passage through any of the apertures 7 in said jaw. The fixed jaw and the swinging jaw are provided, respectively, with serrations 8, 9 at their free extremities for engagement with the work. Within 50 the channeled portion of said fixed jaw a shoe 10 is slidably disposed, which shoe is introduced or removed through the portion 3 of said channel, which is connected by rivets 11 to an angular flexible member 12

which extends to the heel of the swinging 55 jaw and is disposed in a notched portion 13 thereof to retain said jaw in adjusted position upon the work and to cause the jaw 5 to grip, or obtain a purchase upon the work. The shoe 10 is further formed with a bifurcated portion 14 within which one end of a pronged spring 15 which properly positions the shoe 10 with relation to the jaw 5 to cause the flexible member 12 to exert a pressure upon said jaw when the latter is in 60 operative position, is secured by a pin 16 and the prongs of said spring terminate in eyelets 17 that are disposed about the bolt 6 carried by said swinging jaw, and further, said eyelets are formed with laterally extending lugs 18 adapted for engagement with annular grooves formed in the inner or bifurcated end 19 of the swinging jaw 5 which arrangement effectually prevents lateral play of the said swinging jaw with 65 relation to the fixed jaw, and said spring further serves to slide the shoe 10 in the channel 2 as the swinging jaw is adjusted at different points in the fixed jaw. To adjust the jaws 1 and 5 for pipes or work of 70 small diameter the bolt 6 is passed through the aperture 7 in the fixed jaw nearest the handle 4 and for pipes of increasing diameter the said bolt is moved into the apertured portions of the fixed jaw more remote from 75 the handle.

What is claimed is:—

In a pipe wrench, a fixed jaw terminally serrated and having a channeled face and shank, a terminally serrated swinging jaw 90 terminally pivoted in the channeled portion of said fixed jaw; said swinging jaw being formed with a notched heel at its pivotal end, a shoe slidably adjustable in the channeled portion of said fixed jaw, and an angular member carried by said shoe for engagement with the notched heel of said swinging jaw whereby the serrated end of the same may be impelled toward the fixed jaw when pressure is applied to the latter in 95 one direction.

In testimony that I claim the foregoing as my own I have hereto affixed my signature in the presence of two subscribing witnesses.

JOHN A. PETERSON.
